UNITED STATES PATENT OFFICE.

LAWRENCE T. DOUVIER, OF AMBOY, ILLINOIS.

SAFETY DEVICE FOR RAILROAD CROSSINGS.

Application filed January 24, 1924. Serial No. 688,127.

To all whom it may concern:

Be it known that LAWRENCE T. DOUVIER, a citizen of the United States, residing at Amboy, in the county of Lee and State of Illinois, has invented certain new and useful Improvements in Safety Devices for Railroad Crossings, of which the following is a specification.

This invention is in the way of a safety device for railroad crossings and has reference to automatically operated semaphores, and the main object is to provide a device that will cause motorists to check the speed of their vehicles at the approach of a railroad crossing. Another object is to provide such a device wherein the weight of the vehicle will serve to raise the special semaphore arms provided. A further object is to provide a locking device that will automatically prevent the weight of a vehicle from raising the special semaphore arms, from the approach sides of the crossing, upon the approach of a train, yet permit a vehicle caught between the special semaphore arms at the time of locking to raise the said special semaphore arms and escape from the path of the oncoming train. A still further object is to provide a simple and practical device that will efficiently operate, regardless of weather conditions. These and other objects will be apparent from the accompanying drawing and specification.

In the drawing:

Figure 1 is a plan view, sections being broken out to show the construction of the concrete base;

Figure 2 is a plan view showing the working arrangement beneath the road platform; the platform being removed;

Figure 3 is a longitudinal vertical section showing the locking device and the springs;

Figure 4 is a longitudinal vertical section showing the shock absorbing link connection between the road platforms and the special semaphore arms;

Figure 5 is a cross section;

Figure 6 is a detail of the locking device;

Figure 7 is a detail of the shock absorbing link;

Figure 8 is a detail of the laminated springs and channel bases;

Figure 9 is a detail showing the platform leaves journaled in bearings mounted on the concrete base;

Figure 10 is a diagram of the electrical arrangement.

In carrying out this invention I provide a concrete base 1, adjacent a railroad crossing 48, said base being divided into compartments 2, 3 and 4, by the walls 5 and 6. Concrete piers 7 are formed at the junction of the walls 5 and 6. Apertures 8 and 9 are cut in the walls 5 and 6 and rises 10 are formed at the side of the walls 6 for a purpose to be later explained. Tracks 11 are secured on the inner sides of the walls of the base 1 and on both sides of the wall 5. Coil springs 12 and laminated springs 13 are secured to the base 1 in line with the center of the tracks 11. The laminated springs 13 are secured to links 14; the said links 14 are hingedly secured to channel-like bases 15. Primary I beams 16 are placed upon the coil springs 12. The ends 17 of the said primary I beams 16 slidingly engage the tracks 11. Secondary I beams 18 having road platforms 19 secured thereto, are rigidly secured to the primary I beams 16. The ends 20 of the secondary I beams 18 pass through the apertures 9 of walls 6 and have arms 21 secured thereto. Leaves 22 are journaled in bearings 23, and lap over the edges of the road platforms 19 to avoid sudden bumps and to prevent dirt and snow from getting into the base 1. Semaphore bases 24 are secured to the concrete piers 7. Special semaphore arms 25 having red reflectors 26 secured to their forward ends and balancing weights 27 to their rear ends are journaled in the semaphore bases 24. Shock absorbing links 28, consisting of eye bolts 29, turn buckles 30, springs 31, bolts 32 and 33 and plates 34, connect the special semaphore arms 25 with the arms 21. The holes 35 in the plate 34 are of a greater diameter than the bolts 33 to permit raising the special semaphore arms 25, from either side of the semaphore bases 24 without interfering with the opposite side. Locking devices 51 are installed in the compartment 3 underneath the road platforms 19, to prevent raising the special semaphore arms 21 from the approach sides upon the approach of a train. The locking devices 51 comprise bases 36, having bearing supports 37 incorporated therein; locking bars 38 pivotally mounted between the bearing supports 37; and bars 39 and 40 pivoted between the locking bars 110

38. Brackets 41 are secured to the wall 5. Springs 42 are secured by one of their ends to the bars 39 and by their other ends to the brackets 41. Rods 43 having eyes formed in one end and plates secured to the other end, are passed through the apertures 8 of the wall 5 and are secured to the bars 40 by means of links 44. Solenoids 45 are mounted in the compartment 2, in line with the locking devices 51, and when charged with electricity will draw the rods 43 toward them, and hold them there, until the current is cut off. In order to operate the solenoids 45, a battery 46 and a relay 47 are provided. The tracks 48 are insulated as shown at 52 and properly wired up with the solenoids 45, the battery 46 and the relay 47, as shown in Figure 10. A switch 49 is located between the relay 47 and the solenoids 45 to permit the cutting off of the electric current when a train stops at a crossing. Plates 50 having slots cut therein to permit the bolts 33 to pass through them are placed over the compartments 4 and secured to the rises 10 and the walls of the base 1, to prevent dirt and other refuse from getting into the said compartments 4.

In use a semaphore with the above described device is located on each side of the tracks 48.

In operation a vehicle approaching the railroad crossing moves onto the road platform 19 which rests on the coil springs 12 and causes the said coil springs to compress due to the added weight. Upon the compression of the coil springs, the road platform lowers and draws the arms 21 down by means of the secondary I beams 18, thus pulling the shock absorbing link 28 downward and raising the special semaphore arms 25, which permits the vehicle to pass. Normally the locking bars 38 are in a slanting position, being held that way by the springs 42. When a train comes within the insulation upon the tracks 48, the solenoids 45 are charged with electricity causing them to draw the rods 42 toward themselves, overcoming the springs and raising the locking bars, thus locking the road platforms and keeping same locked as long as the train is within the insulation. Upon passing out of the insulation the current is cut off, whereupon the springs again come into play and draw the locking bars into their normal position. Any machine caught between the semaphores at the time of locking may easily escape by raising the special semaphore arms 21 in the usual manner, there being no locking device provided for the road platforms nearest the tracks. The laminated springs 13 are provided to prevent the coil springs from breaking in the event a vehicle of great weight passes onto the road platform.

65 While I have herein described a certain

specific method of constructing and assembling the elements of my invention, it is understood same may be varied in minor details, not departing from the spirit of my invention as defined in the appended claims. 70

I claim:

1. In combination with a railroad crossing having insulated rails; a safety device, comprising a base; tracks, secured to the walls of the base; coil and laminated springs mounted on the base, in line with the tracks; primary I beams, engaging the tracks and resting on the coil springs; secondary I beams, secured to the primary I beams; road platforms, secured to the secondary I beams; arms, secured to the ends of the secondary I beams; semaphore bases, mounted on the base; special semaphore arms, journaled in the semaphore bases; red reflectors, secured to the forward ends of the special semaphore arms; balance weights, secured to the rear ends of the special semaphore arms; shock absorbing links, connecting the rear end of the special semaphore arms with the arms secured to the secondary I beams; leaves, journaled to the base; plates, resting on the base; locking devices, mounted on the base beneath the road platforms; solenoids, mounted on the base beneath the road platforms, to operate the locking devices; a 80 battery, a relay and a switch operatively wired up with the solenoids and the insulated railroad tracks. 85

2. In combination with a railroad crossing, having insulated tracks; a safety device, comprising a base; tracks, secured to the walls of the base; coil springs and channel-like bases, mounted on the base in line with the tracks; laminated springs, hingedly mounted in the channel-like bases; primary I beams resting on the coil springs and engaging the tracks; secondary I beams secured to the primary I beams; road platforms, secured to the secondary I beams; arms, secured to the ends of the secondary I beams; semaphore bases, mounted on the base; special semaphore arms, carrying red reflectors, journaled in the semaphore bases; eye bolts, engaging the special semaphore arms; turnbuckles secured to the eye bolts; springs, mounted in the turnbuckles; bolts, resting on the springs, slidably engaging the turnbuckles; plates, secured to the bolts; bolts, secured to the arms on the secondary I beams slidably engaging the plates; bearings, secured to the base; leaves, journaled in the bearings engaging the road platforms; plates, having slots cut therein to permit bolts to pass therethrough, secured to the walls of the base; tracks, having bearing supports incorporated therein, mounted on the base; stop bars, pivoted in the bearing supports; bars, pivoted to the stop bars; brackets, secured to one of the walls of the base; springs secured to the brackets and 120

some of the bars; rods, having eyes formed therein and plates secured thereto, slidably passed through the above mentioned wall; links, connecting the remaining bars with the aforementioned rods; solenoids, mounted on the base, in line with the said rods, to operate the same; a battery, a relay and a switch, properly wired up with the insulated tracks and the solenoids, to operate the same.

3. A device of the kind described, comprising a base; tracks secured to the walls of the base; primary I beams, engaging the tracks, road platforms, secured to the primary I beams; means for lowering and raising the primary I beams; arms secured to the road platforms; semaphore bases, having arms carrying red reflectors journaled therein, secured to the base; means for connecting the arms secured to the road platforms with the arms journaled in the semaphore bases; means for preventing dirt and

snow from getting beneath the road platforms; means for locking the approach side road platforms; insulated railroad tracks; and means for operating the locking device in connection with the insulated railroad tracks.

4. In a device of the kind described, a base; road platforms slidably mounted in the base; means for lowering and raising the road platforms through the weight of a vehicle; semaphores mounted on the base; means for operating the semaphores through the medium of the road platforms; means for locking the approach side road platforms; and means for operating the locking means upon the approach of a train.

In testimony whereof I affix my signature.

LAWRENCE T. DOUVIER.
